Luke Hale, of Hollis, State of New Hampshire,

6860X

Letters Patent.

The schedule referred to in these Letters Patent and marking part of the same containing a description in the words of the said Luke Hale himself of his improvement in the Standing Prop, called the "Toggle joint standing Prop."

To all persons to whom these presents shall come,

Luke Hale, of Hollis, County of Hillsborough and State of New Hampshire,
Amenistist. - Deigning greetings,

Be it known that I Luke Hale have invented contrivances made and applied to use a new and useful improvement in the Standing Prop, called the "Toggle joint standing prop" which I specify and describe in my own words as follows:

The said Prop for common use is about eight feet high, four and a half feet wide, and one and a half feet deep; the bed piece about twelve inches, and the post four and a half inches thick. The post are framed into the bed piece and beams, by double tenons well fitted to double mortises, made in the bed piece and beams, into which mortising the tenons are forced, and then fastened by four iron bolts passing up through the bed piece and beams having strong heads on the lower end, and strong nuts screwed on the upper end of each bolt. These bolts bind the Prop firmly together. The platten is in length and breadth equal to the width and depth of the frame, and about one foot thick. It has a tenon on each end, exactly fitted so as to slide up and down between the said iron bolts which serve for guides to the platten as well as for efficient supports to resist the power of the prop.

There are four boxes having half round grooves to receive the heads of the toggles, two of which are made fast to the under side of the beams, and the upper two to the upper side of the platten. They are placed at such distances from the ends as to render the power of the toggles as equal as possible on every part of the beam and platten.

On the left hand box on the platten is a flange rising about three or four inches high to guide the lower end of a sling to be described. Each box has a cap with half round groove matching the groove in the box, the caps are made fast to the boxes by bolts or screws. Four long toggle joints in upright positions between the beams and platten, they are made wide with double bars. The bars are connected at

The extreme ends by a round bolt or pivot fitted to the said boxes by which the toggles are connected with and suspended to the beam with all their appendages. Within about three inches of the centre joint of the toggles the side bars have another union by a square bar extending from one side to the other. The inner ends of the side bars are recessed about one third part of a circle fitted to play over pivots to be mentioned hereafter, on the outside of each side bar is a flat hinge which holds the recessed faces of the side bars of the toggles to the above mentioned pivots. These pivots are formed one on each opposite edge of a strong nut of an oblong spherical form placed in the centre of each toggle. The nuts are well fitted on a screw about one and a half inches in diameter, and just long enough to reach from the inside of one part to the inside of the other. This screw is the grand moving principle. It is made with a square thread right-handed, at one end and left-handed at the other end, so that the toggle joints may approach to or recede from each other as the screw is made to revolve, one way or the other. On the centre of this screw is made fast a dented wheel about eighteen inches in diameter, on the right-hand of which and close to it is made fast another dented wheel nearly three feet in diameter, and on the left-hand side of which is swivelled the upper end of a flat sling extending down to the platform, when it is raised to its highest point these entering the above mentioned flange or hollow stud which rises so high as to retain the end of the sling to have the platform at its lowest point. On the right-hand end of the said screw used touching the post is swivelled another sling extending downwards, the lower end of which passes through a staple or bridge screwed to the post; the conuk arbor with its appendages is placed directly below and parallel to the said screw, on the right-hand end is a pivot long enough to reach through the pivot hole in the lower end of the sling, through the post mortised for that purpose, and receive a nut on the end. At the other end it has a long pivot which plays in a pivot hole in the lower end of the left-hand sling; and it has so much end chase, that it may at option be slid one way and the other about two or three inches for the purpose of shifting the gearing. Upon to the shoulder of the pivot on the left-hand end of the arbor is made fast a small wheel, so calibred as to mesh into the smaller wheel on the said screw, about one or three inches to the right of said small wheel on the same arbor is made fast a small pinion of eight or ten tuns calibred to mesh into the larger wheel on the said screw, by which

6860X

means the operator can apply a smaller or greater power, or operate with a greater or less hand at option.

What I claim as my invention and improvement, is the application of the right and left handed screw by which the trigger points are put into action, all other parts being common. In testimony that the above is a true specification of my said improvement I have this day set my hand and seal this 29th day of November in the year of our Lord one thousand eight hundred and thirty one
